JOSEPH C. FIELD, OF ORANGE, NEW JERSEY, ASSIGNOR TO WESTERN ELECTRIC COMPANY, OF NEW YORK, N. Y., A CORPORATION OF ILLINOIS.

SELECTIVE SIGNALING SYSTEM.

1,125,997.

Specification of Letters Patent.

Patented Jan. 26, 1915.

Application filed August 23, 1912. Serial No. 716,644.

To all whom it may concern:

Be it known that I, JOSEPH C. FIELD, a citizen of the United States, residing at Orange, in the county of Essex and State 5 of New Jersey, have invented a certain new and useful Improvement in Selective Signaling Systems, of which the following is a full, clear, concise, and exact description.

This invention relates to selective signaling systems of that class comprising a sending station and a plurality of way stations, each way station being equipped with selective apparatus responsive to a predetermined character or combination of current 10 impulses, sent out from the sending station, to operate a local signal.

The object of the invention is to provide means in connection with such a system for impressing impulses upon the line of a character 20 to operate a signaling device connected in series with the selector without effecting the operation of the selective apparatus or interfering with any conversation which might be taking place as the signaling impulses 25 are being sent out.

The principal feature of this invention is the provision of a condenser combination by means of which time sending impulses from a telegraph line will, with the same 30 battery supply as is used to operate the selectors, impress upon the line, potentials of alternately opposite polarity approximately twice the potential of the source of supply and will cause such a gradual emission and 35 extinction of the current impulses that telephonic apparatus will be unaffected thereby.

In accordance with this invention there is provided at the sending station a pole changing relay operating in response to impulses 40 over a telegraph line or other extraneous source to connect a source of current with the line wires and two condensers, one connected in bridge of the line wires to discharge through the signal device 45 to prolong the impulse caused by the discharge of the other which is associated with the contacts of the pole changing relay in such manner as to be alternately discharged and charged to produce a momentary impulse 50 over the line wires and through the signal greater than the normal battery voltage.

In the drawings illustrating this invention—Figure 1 is a diagram of the apparatus and connections of a straight train 55 despaching scheme embodying this invention.

tion, and Fig. 2 is a diagram of the apparatus and connections of an intercommunicating train despaching scheme embodying this invention.

In the two figures of the drawing 1 and 2 designate the line wires, A the despatcher's station and B and C way-stations on the line. Connected in the line wires 1 and 2 are retardation coils 3 and 4 operating in conjunction with a condenser 5 60 bridged across the line wires to smooth out or graduate the current impulses transmitted for operating the selector so that they will not affect telephone apparatus which may be connected with the line during 70 the operation of a selector.

Located at each of the waystations is a selector mechanism comprising slow and quick acting magnets 11 and 12 and a ratchet wheel 13 controlled thereby through 75 the medium of stepping and holding pawls 14 and 15. Attached to the ratchet wheel 13 is a contact arm 16 adapted in the rotation of said ratchet wheel to be brought into contact with the anvil 17 to complete a circuit through a vibrating bell 18 for signaling 80 the waystation operator.

The line wires 1 and 2 of each scheme are connected with the studs of a double pole double throw switch 20, the other studs of 85 which are connected with contacts of an impulse relay 21 and a pole changing relay 22 respectively. In the scheme shown in Fig. 1, one pair of the studs of the switch 20 is connected directly with normally open 90 contacts of the impulse relay 21, the armature levers 23 and 24 of which are connected with the opposite poles of a battery 25. An impulse transmitter 26 with a condenser and a resistance in shunt with the 95 impulse relay 21 and a local battery 27 is adapted to intermittently close the circuit through the relay 21 to send impulses over the line for operating the selectors.

In the scheme shown in Fig. 2, the impulse relay is adapted to be operated from any one of the sending stations by means of a key 30 arranged to connect ground with both of the line wires. For this purpose the line wires 1 and 2 are connected 105 directly with the winding of the impulse relay 21 through a source of current 25 and the impulse relay is provided with contact 31 and armature 32 operating when the relay is energized to open the circuit over 110

one of the line wires and connect the source of current in bridge thereof. The impulse relay of the scheme shown in Fig. 2 may be operated from a local transmitter key 33. The pole changing relay 22 in both schemes is connected in circuit with the source of energy 25 through a contact 38 on a relay 39 the winding of which is connected in circuit to respond to impulses over a telegraph line or a standard time wire over which time impulses are sent from the National Observatory at Washington, D. C. Located at each of the waystations is a non-biased polarized ringer 40 which is bridged across the line wires 1 and 2 in series with the selector magnets 11 and 12. This ringer operates in response to alternating current impulses over the line wires 1 and 2 and in consonance with the relay 39. The arrangement for sending the alternating impulses to which the ringers respond is as follows:

As shown the contact armatures 45 and 46 of the pole changing relay 22 are connected with the opposite poles of the source of energy 25 and each is adapted to make and break a pair of contacts 47, 48, and 49, 50 respectively to connect a condenser 55 in series with the source of current 25. The condenser 55 is so arranged that it will first be charged to the full potential of the battery 25 in one direction through the contacts 47 and 49. Upon reversal of the battery by the operation of the relays 39 and 22 the condenser 55 is discharged through the signal 40 in series with the source 25 and charged in the opposite direction to the full potential of the battery 25 through the contacts 48 and 50, thus giving the equivalent of twice the voltage of the battery 25 for sending the reversed current impulses over the line. The condenser 5 across the line at the sending end is charged on each reversal of the sending battery but only remains charged until the condenser 55 in series with the line has become fully charged. When this occurs there is no current flowing, the potential across the line becomes zero and the condenser 5 across the line will discharge and send current out over the line in the same direction as the last impulse due to the charging of the condenser 55 in series with the line. This discharge of condenser 5 tends to prolong each current impulse sent over the line and through the ringers. This may be more clearly seen by tracing in detail the paths of the currents which are as follows: Assuming that the switch 20 is thrown to the right or into position to connect the line wires 1 and 2 with the contacts of the relay 22. If the relay 22 is deenergized there will be a path for current as follows: from the minus side of the battery 25 through contact 49 of the relay 22, one

blade of the switch 20, conductor 2, parallel paths one of which includes the condenser 5 and the other the selector bridge, including magnets 11 and 12 and the ringer 40 to line wire 1, through the other blade of the switch 20 to the condenser 55 and through contact 47 of relay 22 to the opposite side of the battery 25. Current in this path will charge both of the condensers 5 and 55, the condenser 55 to practically the normal voltage, the condenser 5 to possibly half or less than that of the condenser 55 depending upon the impedance of the selector bridges. As the condenser 55 becomes charged, however, and the potential across the line wires approaches or becomes zero, the condenser 5 will discharge out over the line wires 1 and 2, the current from this discharge being in the same direction over the line wires as the impulse which charged the condensers, thus prolonging the current impulse through the ringer 40. If now the relay 39 is operated to close the circuit of the relay 22 to open the contacts 47 and 49 and close the contacts 48 and 50, there will be completed a discharge path for the condenser 55 which may be traced as follows: from the minus side of the battery 25 through contact 50, condenser 55 one blade of the switch 20; line wire 1 the bridge including the electromagnets 11 and 12 and the ringer 40, line wire 2, the other blade of the switch 20, contact 48 of the relay 22 to the plus side of the battery. This will give a momentary surge of current over the line wires and through the condenser 5 and the selector bridges of a total equal to the amount of the charge on the condenser 55 and the voltage of the battery 25. As soon as this momentary surge has ceased and the condenser 55 has entirely discharged it will charge in the opposite direction. When it has become charged and no current is flowing the condenser 5 will discharge over the line wires in the direction of the last charging impulse of the battery 25, thus prolonging the current impulse through the ringer 40. Similar operations will follow each operation of the relay 22 and reverse current impulses of equivalent to practically twice the voltage of the battery 25 will be sent over the line wires through the ringer 40 which will tap one of its gongs for each reversal.

With a scheme such as hereinbefore described there is but a very low intermittent current drain upon the sending battery while sending time.

The cost of additional apparatus for equipping any line is very slight and may be added to any existing circuits without change and conversation may be carried on over a line so equipped if desired while time signals are being sent.

I claim:

1. In a selective signaling system, line 130

- wires, a sending station and a way station connected therewith, a source of current at said sending station, means thereat for sending current impulses, a selector at said way station including a slow acting holding magnet responsive to current impulses, a polarized signaling device at said way station in bridge of said line wires and in series with said slow acting holding magnet, reversing means at said sending station for applying current from said source to said line alternately in opposite directions, and means at said sending station alternately charged and discharged in the operation of said reversing means for operating said polarized signal and preventing the operation of said slow acting holding magnet.
2. In a selective signaling system, line wires, a sending station and a way station connected therewith, a source of current at said sending station, means thereat for sending current impulses, a selector at said way station including a slow acting holding magnet responsive to current impulses, a polarized signaling device at said way station in bridge of said line wires and in series with said slow acting holding magnet, reversing means at said sending station for applying current from said source to said line wires alternately in opposite directions, and a condenser at said sending station connected with said line in the operation of said re-
- versing means and alternately charged and discharged at each reversal for operating said polarized signal and preventing the operation of said slow acting holding magnet.
3. In a selective signaling system, line wires, a sending station and a way station connected therewith, a source of current at said sending station, means thereat for sending current impulses, a selector at said way station including a slow acting holding magnet responsive to current impulses, a polarized signaling device at said way station in bridge of said line wires and in series with said selector, reversing means at said sending station for applying current from said source to said line alternately in opposite directions, and a condenser in series with said line wires at said sending station alternately charged and discharged in the operation of said reversing means for giving momentary discharges over said line wires whereby said polarized signal is operated and the operation of said slow acting magnet is prevented.

In witness whereof, I hereunto subscribe my name this 22nd day of August, A. D. 1912.

JOSEPH C. FIELD.
